GARMENT CLEANING SYSTEM

Filed Aug. 16, 1935

FIG. - 1

BY
Brackett, Hyde, Higley & Meyer
ATTORNEYS.

UNITED STATES PATENT OFFICE

2,130,817

GARMENT CLEANING SYSTEM

Julian C. Shaw, Norwood, Ohio, assignor to The American Laundry Machinery Company, Norwood, Ohio, a corporation of Ohio

Application August 16, 1935, Serial No. 36,545

4 Claims. (Cl. 8—5)

My invention relates to fabric cleaning systems, and more particularly to an improved system for washing or cleaning fabric and clarifying or reclaiming the treating liquid or solvent.

5 In processes heretofore utilized in washing or cleaning fabric in which a treating or cleaning fluid, such as gasoline, benzine, or synthetic cleaning solvents, such as carbon tetrachloride, or water containing soap or a suitable detergent, is employed, it has been the practice to utilize the batch or a continuous clarification process.

10 In the batch process, the fabric is treated in a bath of the cleaning fluid or solvent, or with two or more intermittent baths, the solvent or treating medium being discharged after each treatment. In the continuous clarification system, the treating vessel is connected with a clarification unit, such as a filter, and during the entire cleaning cycle the fabric is treated in a bath 15 of solvent which is being continuously circulated through the treating vessel and clarification system.

15 The batch system is advantageous in that a comparatively rapid removal of the grease, dirt and other suspended matter is effected, and since the cleaning fluid or solvent is drained from the fabric at the end of each treatment, suspended matter which is removed from the fabric is not redeposited.

20 In the continuous clarification system the treating or cleaning fluid is being constantly clarified and reutilized, but as the suspended matter removed in the treating vessel is being continuously diluted with clean fluid, the system is not very efficient, in other words, in the continuous method there is a waste of clean fluid because it is being continuously mixed with fluid containing suspended matter.

25 I have provided an improved system in which fabric or garments may be washed or cleaned in a liquid or solvent and the cleaning liquid continuously clarified and returned for reuse in the process which is operated in such a manner that the clarified liquid or solvent will not be mixed 30 with the used solvent in the treating vessel.

35 It is therefore an object of my invention to provide an improved system by means of which fabric or garments may be washed or cleaned in batches, in combination with a continuous clarification system in which dirt or other matter may be removed from the liquid or solvent which is returned for reuse in the process. Another object of my invention is to provide an improved system in which a sufficient amount of liquid or 40 solvent is supplied for washing or cleaning a

batch of garments at predetermined intervals, in which the washing or cleaning operation is conducted for a predetermined interval of time, and in which continuous means are provided for clarifying or reclaiming the liquid. A further object 5 of my invention is to provide a combined cleaning and clarification system that is substantially closed against communication with the atmosphere, and which is provided with an improved venting system for equalizing the pressure in the 10 system. A still further object of my invention is to provide a cleaning and clarification system in which improved means are provided for controlling the supply and discharge of cleaning fluid to the treating vessel.

15 My invention will be better understood by references to the accompanying drawing in which:

Fig. 1 is a diagrammatic view of my improved system; and

Fig. 2 is a view taken on the line 2—2 of Fig. 1, 20 showing parts broken away.

As illustrated in the drawing, my improved system comprises a treating vessel 1 provided with the usual rotatable goods container 2. Arranged above the treating vessel 1 is a storage tank 3 25 which communicates with the treating vessel 1 through a conduit 4 which is controlled by valves 5 and 6. During the operation of the system valve 5 is in open position and is closed when the system is idle. A drain pipe 7 controlled by a 30 valve 8 leads from the lower portion of the treating vessel to a sump tank or collecting vessel 9, and a conduit 10 controlled by a valve 11 leads from the sump tank 9 and is connected to the inlet side of a pump 12, the outlet side of which 35 is connected by conduit 13 to a clarification unit 14. The clarification unit 14 may be of any suitable type capable of removing suspended matter from the cleaning fluid, such as a filter, a centrifugal or chemical clarifier, or a still and condenser. The clarified liquid is then forced 40 through a conduit 15, controlled by a valve 16, into the storage tank 3. If a still and condenser are employed, the condenser may be located above the storage tank, as illustrated in Patent No. 45 1,995,064 to Russell A. Hetzer, and if a centrifuge is employed, an additional pump may be provided to force the liquid into storage tank 3.

The clarification system is also provided with a conduit 18 extending from conduit 15 to the 50 sump tank 9 so that by closing valve 16 liquid may be pumped from the sump tank through the clarification unit and again returned to the sump tank for recirculation through the filter. By repeatedly circulating the soiled liquid through the 55

filter, removal of all or substantially all of the suspended matter will be assured. A branch conduit 19 leading from the storage tank 3 to the intake side of the pump 12, which communicates with the conduit 10 at a point indicated by the numeral 21, provides means for passing liquid from the storage tank through the clarification unit and returning it again to the storage tank. By opening valves 11 and 20 and discontinuing the operation of the pump 12, liquid may also be drained from the storage tank directly to the sump tank.

A venting arrangement is also provided comprising a conduit 22 which leads from the upper portion of treating vessel 1 to the upper portion of the sump tank 9 which equalizes the pressure in those two vessels and a conduit 23 extending from the upper portion of storage tank 3 to the upper portion of sump tank 9 which equalizes the pressure in the storage and sump tanks.

Valve 6 is provided with a stem 25 which extends through apertures in the bottom and head of a longitudinally disposed cylinder 26 and is affixed to a piston 27 which reciprocates in the cylinder with the stem 25. The head 28 of the cylinder is provided with a vent 29 and coiled around the stem 25 between the piston 27 and the head 28 is a spring 30 which normally forces valve 6 to closed position.

In a like manner the stem 31 of valve 8 extends through apertures in the bottom and head of cylinder 32 and is affixed to a piston 33 which reciprocates with the stem in the cylinder 32. The head 34 of cylinder 32 is also provided with a vent 35 and a spring 36 coiled around stem 31 is disposed between the head 36 and the piston 33 which normally forces valve 8 to closed position. It will be noted that when valves 6 and 8 are in closed position, pistons 27 and 33 are in spaced relationship with the bottom of the respective cylinders, forming air chambers from which conduits 40 and 41 lead to valve casings 42 and 43, respectively.

Valve casing 42 is provided with partitions in which ports 46 and 47 are formed. The partitions also provide seats for valves 48 and 49 which are connected together by a valve stem 50 which extends through the ports 46 and 47 and through apertures in the ends of the casing. In a like manner valve casing 43 is provided with partitions in which ports 51 and 58 are formed, the partitions providing seats for valves 59 and 60. Valves 59 and 60 are connected together by a stem 61 which extends through ports 51 and 58 and through apertures in the ends of casing 43.

A spring 64 coiled around valve stem 50 is disposed between the valve 49 and one end of casing 42 which normally maintains valve 48 in open position and valve 49 in closed position. In a like manner a spring 65 is coiled around valve stem 61 between the valve 56 and one end of valve casing 43 which normally maintains valve 59 in open position and valve 60 in closed position. Casings 42 and 43 are each provided with an exhaust port 66 and 67, respectively.

Valve stems 50 and 61 are actuated by means of cams 69 and 70 fixed to a drum 68. Drum 68 is provided with journals 73 and 73a which are rotatably mounted in suitable bearings 71 and 72, the journal 73 of the drum being provided with a gear 74 which meshes with a worm gear 75 attached to the shaft 16 of a motor 71.

A suitable fluid under pressure, such as air, is supplied to the portion of casing 42 controlled

by valve 49 and to the portion of casing 43 controlled by valve 60. As illustrated, the fluid pressure is supplied from a suitable source through conduit 78 which is provided with a branch 79 leading to casing 42 and a branch 80 leading to casing 43.

In the operation of my improved system, cylinder 68 is rotated by motor 71, and as cam 69 engages valve stem 50 it forces valve 48 to its seat and opens valve 49 against the action of spring 64. Fluid under pressure from conduits 78 and 79 then enters casing 42, passes through port 47 and conduit 40 into the servo-motor 26, forcing piston 27 outwardly against the action of spring 30, thereby opening valve 6. Assuming that valve 5 is open, the solvent or cleaning medium then passes from the storage tank 3 into treating vessel 1. As the rotation of cylinder 68 is continued, cam 69 passes from engagement with valve stem 50 and spring 64 forces valve 49 to closed position and opens valve 48. Air under pressure in cylinder 26 then passes through the conduit 40 and ports 46 and 66 to the atmosphere and spring 30 forces the valve 6 to closed position. As cylinder 68 is rotated still further, the cam 70 on the cylinder 68 engages valve stem 61, opening the valve 60 and closing the valve 59. Air under pressure then passes through conduits 78 and 80, port 58 and conduit 41 to servo-motor 32, forcing the piston 33 outwardly against the action of spring 36 and opening valve 8. While the cam 70 is in engagement with valve stem 61, the soiled liquid or solvent is drained from the treating vessel.

It will be noted that cams 69 and 70 are arranged upon drum 68 in such a manner that after the solvent or cleaning liquid has been introduced into the treating vessel, sufficient time is permitted for the washing operation before valve 8 is opened to drain the used solvent into the sump tank. During the period in which the cleaning agent or solvent is being introduced and drained from the treating vessel, and also during the washing period, the soiled liquid is being pumped from the sump tank 9 and forced through the conduit 13 and clarification unit 14 into the storage tank 3. If it is desired to recirculate the soiled liquid through the filter, valve 24 is opened and valve 16 is closed, and after the liquid has been passed through the filter a sufficient number of times to clarify the liquid, valve 24 is closed and valve 16 is opened and the liquid is passed into storage tank 3. Instead of passing the filtered liquid back to the sump tank through the pipe 18, valves 16 and 20 may be opened and valves 24 and 11 closed, and liquid from the storage tank 3 may be passed through the conduit 18 and recirculated through the clarification unit.

My improved venting arrangement comprising conduits 22 and 23 equalizes the pressure within the system which, as shown, is closed or substantially closed against entrance of air. For instance, when liquid is being drained into the sump tank 9 from the treating vessel 1, the air displaced in the sump tank is conducted into the treating vessel through the conduit 22. When soiled liquid is pumped from the sump tank through the clarification unit and into the storage tank, the air displaced in the storage tank passes into the sump tank through the conduit 23, and when the treating compartment is being

filled, the air displaced therein is passed into the sump tank and to the storage tank through the conduits 22 and 23. If it is desired to drain the contents of storage tank 3 into the sump tank through conduits 19 and 10, the air displaced in the sump tank is passed into the storage tank through the conduit 23. By this arrangement of conduits, it will be seen that the system may be completely closed and equalization of pressure within the system may be obtained.

From the foregoing specification, it will be apparent that I have provided an improved system in which the advantages of both the batch and the continuous clarification systems are obtained. By utilizing my improved system, it will be seen that it is not necessary to use such a large clarification unit, or if the same size clarification unit is employed, two or more cleaning units may be used in connection with each clarification system. Assuming, for example, that the clarification system has a capacity of 1200 gallons of solvent or cleaning liquid per hour and that the washing cycle is 15 minutes. In the continuous system 300 gallons of liquid pass through the treating vessel and clarification system during a cleaning cycle. In a batch system of equal cleaning capacity it takes approximately fifteen gallons to produce the same level of liquid in the treating compartment as that produced by the use of 1,200 gallons per hour in the continuous system. In accordance with my invention, if ten separate baths are employed, each bath requiring a period of time including fifteen seconds to fill, sixty seconds to wash and fifteen seconds to drain, this would be equivalent to a fifteen minute operation in the continuous system. In such operation, however, only 150 gallons of the cleaning or solvent fluid would be employed as compared to 300 gallons when the continuous system is utilized. The same clarification system could therefore be utilized with two cleaning units, or a clarification system having only one-half the capacity of that utilized in the continuous method could be employed.

The foregoing example illustrates a washing operation in which ten separate baths are employed. If the number of baths are reduced, however, it might be possible in my improved system to employ as many as four units in connection with a clarification system of the capacity specified, whereas, only one cleaning unit can be employed when the usual continuous clarification system is utilized.

Since the location of cams 69 and 70 upon drum 68 automatically determines the time of operation of valves 6 and 8, it will also be seen that my improved system is substantially automatic in operation and will therefore require substantially no manual attention.

It will be understood that the term "clarification unit" as employed in the specification, and claims is not only intended to include a filter or centrifugal or chemical clarifier, but also other clarifying or reclaiming units or apparatus in which suspended matter or impurities may be removed from the used treating fluid or solvent. For example, in place of the filter, a still and condenser may be employed in which case not only the suspended matter but also soluble impurities, such as grease, may be removed.

To those skilled in the art many modifications of and widely different embodiments and applica-

tions of my invention will suggest themselves without departing from the spirit and scope thereof. My disclosure and description herein are purely illustrative and are not intended to be in any sense limiting.

What I claim is:

1. In a system for treating fabric, a storage tank, a collecting vessel, a treating vessel communicating with the storage tank and the collecting vessel, a clarification unit, communicating means between the collecting vessel and the inlet of the clarification unit and communicating means between the outlet of the clarification unit and the storage tank and between the outlet of the clarification unit and the collecting vessel, and means for forcing used liquid from the collecting vessel through the clarification unit and alternatively passing it either to the storage tank or returning it to the collecting vessel for recirculation through the clarification unit without passing it through the treating vessel.

2. The process of cleaning fabric which comprises intermittently supplying solvent to fabric from a supply tank at repeated intervals of comparatively short duration, treating the fabric for a comparatively short period between the intervals at which solvent is supplied to the fabric, draining the fluid from the fabric into a sump tank after each treating operation and continuously passing used liquid from the sump tank through a filter and returning it to the supply tank during the fabric treating operations and while solvent is being supplied to and drained from the treating apparatus at a rate which is approximately just sufficient to supply additional clarified liquid for each treating operation.

3. The process of cleaning fabric which comprises intermittently supplying solvent to fabric from a supply tank at repeated intervals of comparatively short duration, washing the fabric for a period of approximately sixty seconds between the intervals at which solvent is supplied, draining the liquid from the fabric after each treating operation into a sump tank and continuously passing used liquid from the sump tank through a filter and returning it to the supply tank during fabric treating operations and during the periods at which solvent is being supplied and drained from the treating apparatus at a rate which is approximately just sufficient to supply additional clarified liquid for each treating operation.

4. The process of treating fabric which comprises intermittently supplying solvent to fabric from a supply tank at repeated intervals of comparatively short duration, washing the fabric for a period of time approximating a minute between the supply intervals, draining the liquid from the fabric into a sump tank after each washing operation, the number of washing operations being sufficient to clean the fabric and being substantially in excess of the usual washing and rinsing operations employed in the batch system, and continuously passing used liquid from the sump tank through a filter and returning it to the supply tank during fabric treating operations and during the periods at which solvent is being supplied and drained from the treating apparatus at a rate which is approximately just sufficient to supply additional clarified liquid for each treating operation.

JULIAN C. SHAW.
